United States Patent Office.

T. W. COWEY, OF CANNONSBURG, PENNSYLVANIA.

Letters Patent No. 86,816, dated February 9, 1869.

IMPROVEMENT IN BOTTLE-FILLERS AND CORKERS.

The Schedule referred to in these Letters Patent and making part of the same.

To all whom it may concern:

Be it known that I, T. W. COWEY, of Cannonsburg, in the county of Washington, and State of Pennsylvania, have invented a new and improved Bottle-Filler and Corker; and I do hereby declare that the following is a full, clear, and exact description of the construction and operation of the same, reference being had to the accompanying drawings, making a part of this specification, in which—

Figure 1 is a plan view;

Figure 2 is a side elevation;

Figure 3 is a vertical section of the corking-device; and

Figure 4 is a vertical section of the filling-device.

This invention consists, in the first place, in adapting to a vessel for receiving liquids from the barrel, preparatory to the bottling and corking-processes, an automatic device for regulating the quantity to be drawn off; second, in a peculiar and novel apparatus for filling bottles from the aforesaid vessel; third, in a peculiar and novel device for corking bottles after being filled.

In the drawings, A represents a receptacle, made of sheet-metal, or glass, or porcelain, and of a capacity to suit the needs of the employer, the vessel being intended to receive liquor from the barrels containing it.

Said receptacle is provided with a vertical bail, C, rigidly attached, in any suitable manner.

Through the tops of the bail C passes a short, perpendicular tube, a, rigidly connected with the bail.

Through the tube a passes a small rod, b, sliding freely.

The upper part of the rod is provided with a screw-thread, on which is placed a crank, b'. When the crank b' is in contact with the upper end of the tube a, by rotating it, the rod b may be raised or lowered, as desired.

To the lower end of the rod b is firmly attached the upper end of a vertical pipe, or tube, c, which rests, in suitable supports, in the receptacle, so as to be capable of receiving an up-and-down motion from the aforesaid screw-thread.

A horizontal pipe, c', opens into the pipe c, through which pipes the liquor is drawn off from the barrel.

A float, d, of nearly the diameter of the receptacle A, slides on the vertical pipe c, by means of any suitable attaching-device, such as arms d', connecting the float with a tube, e, sliding on the pipe c.

The tube e is long enough to cover the orifice in the side of the pipe c, through which the liquor flows into the receptacle.

By means of the float and tube, the liquor is made to shut off its own flow.

The height of the liquor in the receptacle, at which the flow is shut off, is regulated by the crank b'.

The liquor passes from the receptacle, through a glass tube, h, into a horizontal, semicircular pipe, i, supported, by brackets, upon the frame B.

The pipe i is provided, at its under side, with as many smaller vertical pipes k as may be desired, each of which has an opening, k', fig. 4, at its lower end, the length of each pipe k being such as to make it form, in connection with the pipes h and i, a siphon.

To each pipe k is fitted a sliding bottling-guide, consisting of a horizontal disk, l, connected, by three or more vertical rods l', to a ring, l'', and a tube, l''', fastened, at its top, to the under side of the disk l, and fitting, pretty closely, the pipe k.

When the lower end of the tube l''' rests against the flange on the lower end of the pipe k, the orifice k' of the latter is closed. To open it, the tube l''' must be pushed up above the hole k'. This is done, in my machine, by the bottle itself.

Each bottle c (as many as there are pipes k) is placed in a hole, m, in the round table D, the bottom of the bottle resting upon a disk, m', rigidly attached to the top of a stud, m'', each stud passing through the corresponding table D', situated at a convenient distance below the other. The lower end of each stud m'' rests upon the platform E, said platform being connected, by sockets, with the vertical posts B', so as to slide up and down thereon, under the action of springs n, attached, at their upper ends, to the cross-beam B, which springs tend to keep the platform E in contact with the round table D', and, consequently, the disks m' in contact with the table D.

The platform E, with its disks, is lowered by the action of a foot-lever, F, connected, at one end, to a shaft, F', suitably supported in a frame of its own, which shaft bears an arm, F'', which rests upon the platform E.

The bottles c, having been placed on their disks m', and brought under the pipes k, the springs n elevate them, so as to bring the neck of each bottle within the ring l''. The head of the bottle strikes the disk l, or a cushion, o, on the under side of each disk, thus raising the tube l''' above the orifice k', and setting the stream of liquor in motion, to fill the bottle.

An air-pump, i', is placed in the tops of the pipe i, to facilitate the first flow of the liquor through the pipes, after which, it flows of itself.

The surface of the liquor in the receptacle A being set, by the regulator before described, higher than the orifice k', the liquor flows into the bottles on the siphon-principle, and when it rises in each bottle to the height of the liquor in the receptacle, the flow stops, as a matter of course. I thus avoid all waste in filling. The quantity in the receptacle varies but slightly, owing to the working of the regulator.

The bottles having been filled, the catch r, that retains the table D, is withdrawn by pressing back the lever r', pivoted to the upright B, and the table D rotated on its pivot, bringing a set of empty bottles under the fillers, and carrying the full bottles around, under the corking-apparatus.

This consists of two uprights, G G, supported in a

suitable position in reference to the table D, and connected, at their tops, by the bar G'. A horizontal connecting-rod, H, joins two tubes, s s, which slide upon the vertical guides G.

To the under side of the connecting-rod H is attached a curved bar, I, from the under side of which projects vertically downward, a number (as many as there are bottles to be corked) of plungers, t. Each plunger slides in a vertical tube, t', suitably attached to the bar I for support, and, at its lower end, expanding into a funnel, t'', to receive the head of the bottle.

The tube t' has a magazine, v, opening into it at one side, and filled with corks.

The magazine is supplied with corks through a pipe, u, of a diameter suited to the size of the corks to be employed, (as is the tube t'), the corks resting, one above another, in the pipe.

A feeder, v', plays in the magazine v, the rear end of said feeder being connected with the lower end of a rod, v'', which is bent inward, near its upper end, so as to be pivoted to the pipe u, and is then bent outward, so as to pass through a slot, W, in the curved plate w, which is attached to the uprights G at about the same height as the curved bar I, and is concentric therewith.

The connecting-rod H, with all its paraphernalia, is drawn downward by the action of a foot-lever, K, joined to the bar H by a connecting-wire, x, the lever K being suitably pivoted to a post, M'.

The tubes t', in which are corks, as shown at y, descend, with the rest, until the funnels t'' come in contact with the tops of the bottles, when they stop, and the plungers t continue to descend through them, forcing the corks into the mouth of the bottles.

At the same time that the tubes t' and u pause in their descent, the lower ends of the bent levers v'' come in contact with the tops of the slots w', thus forcing the lower ends of said levers outward, and withdrawing the feeders v' from beneath the tubes u. This allows a cork to slip from each tube, u, into each magazine, v, which corks, when the magazine rises again, are pushed before the feeders in the tubes t', the feeders being forced inward by the bent levers v'' coming in contact with the upper ends of the slots w' as the tube u rises.

The rising of the bar H, with its tubes and plungers, is due to the retractive force of the spring z.

The bottles are now corked and ready to be removed.

This is effected by swinging back the foundation M, in which the uprights G G are supported, said foundation being pivoted, at one end, to the floor N.

The foundation M being swung back, with the whole corking-machinery just described, the table D is laid open, and the filled bottles may be easily removed from it, and an empty set supplied.

In practice, I design to have three sets of bottles on the tables at once—one set filling, one being corked, and the third, removed.

The machine may, of course, be made large enough to accommodate any desired number of bottles.

The pipe h is made of glass, so that the operator can see when the bottles are filled, by the liquor ceasing to flow.

Having thus described my invention,

What I claim as new, and desire to secure by Letters Patent, is—

1. The float d provided with the tube e, in combination with the pipe c', rod b, tube a', and bail C, for the purpose of regulating the height of liquor in the receptacle A, and keeping its quantity uniform, substantially as described.

2. The circular pipe i, provided with the filling-pipes K, in combination with the feeding-pipe h, arranged in the manner described.

3. The disk l, in combination with the guide, consisting of the rods l' and ring l'', substantially as described.

4. The turn-table D D', in combination with the disk m', stud m'' m'', platform E, and spring n, and lever F, as and for the purpose described.

5. In a bottling and filling-machine, the turn-table D D', as and for the purpose specified.

6. The connecting-bar H, in combination with the curved rod I and plungers t, for corking any number of bottles at a time.

7. The magazine V, in combination with the feeder v', the tubes u and t', lever v'', and slotted plate w, in the manner and for the purpose specified.

To the above specification of my improvement, I have signed my hand, this 7th day of September, 1868.

T. W. COWEY.
